(57) **CLAIM**

The ornamental design for a battery powered personal transportation vehicle for standing rider, as shown and described.

DESCRIPTION

FIG. 1 is a front view.

FIG. 2 is a left side view.

FIG. 3 is a right side view.

FIG. 4 is a back view.

FIG. 5 is a top view.

FIG. 6 is a bottom view.

FIG. 7 is a perspective view.

FIG. 8 is another perspective view; and,

FIG. 9 is the perspective view of FIG. 8, with a representative standing rider shown in dashed lines.

The broken lines throughout the various views are for the purpose of illustrating portions of the vehicle and environmental subject matter that form no part of the claimed design.

1 Claim, 9 Drawing Sheets
